UNITED STATES PATENT OFFICE.

WILLIAM A. MURRAY, OF BALTIMORE, MARYLAND.

MOISTENER FOR GUMMED SURFACES.

SPECIFICATION forming part of Letters Patent No. 673,918, dated May 14, 1901.

Application filed September 28, 1900. Serial No. 31,378. (No model.)

To all whom it may concern:

Be it known that I, WILLIAM A. MURRAY, a citizen of the United States, residing at Baltimore, in the State of Maryland, have invented 5 certain new and useful Improvements in Moisteners for Gummed Surfaces, of which the following is a specification.

This invention relates to an improved device for moistening gummed surfaces.

10 One object of my invention is to provide a device with a chamber for the reception of water having a discharge-orifice at one end controlled by a valve whereby the flow of water to the sponge or other absorbent material used may be controlled and the desired 15 dampness of the sponge maintained.

A further object of my invention is to provide a sponge-receptacle of such a construction as to allow the device to be held in a horizontal position when in use.

20 Other features of the invention will be fully set forth in the description of the accompanying drawings, in which—

Figure 1 is a view showing my improved 25 device being applied to the gummed surface of an envelop. Fig. 2 is a vertical central section of same. Fig. 3 is an inverted plan view of the valve for controlling the flow of water to the sponge.

30 Similar numerals refer to like and corresponding parts throughout the several views.

In the accompanying drawings, 1 designates the water-chamber, 2 the valve for controlling the flow of water to the sponge, and 3 the 35 sponge-receptacle.

The water-chamber in this instance is cylindrical in cross-section and is made of glass. At one end the said chamber 1 is provided 40 with a sleeve 4, held thereto by cement or other suitable material and having its exterior surface screw-threaded for the reception of the cap 5 to close the end of the said water-chamber. At the opposite end the said chamber 1 is provided with a cap 6, having a discharge-orifice 7 therein. The upper surface 45 of the cap 6 is provided with a concavity 8 around the orifice 7 to form a seat for the protuberance 9 when the said orifice is closed. The exterior surface of the said cap 6 is screw-threaded for the reception of the cup-shaped 50 valve 2, the purpose of which will hereinafter appear.

The cup-shaped valve 2 is screw-threaded

on its interior surface at one end to fit over the cap 6. The said valve is also provided 55 with one or more apertures 10 therein, through which the water flows from the chamber 1 to the sponge. Projecting inwardly from the said valve 2 is a protuberance 9, which fits within the concavity 8 of the cap 6 to control 60 the flow of water from the chamber 1 to the sponge 11. The upper end of the valve 2 is screw-threaded on its exterior surface for the reception of the sponge-receptacle 3.

The sponge-receptacle 3 is provided with an 65 interior screw-thread to fit over the valve 2. The opposite end of the said sponge-receptacle 3 is provided with an angularly-disposed opening through which the sponge 11 projects, whereby the said sponge projects at 70 right angles with respect to the water-chamber and permits the device to be held in a horizontal position when in use. The said sponge-receptacle 3 is also provided with an inwardly-projecting pin 12 to retain the 75 sponge in its proper position.

When it is desired to use the device, the valve 2 is unscrewed sufficiently to allow the discharge-orifice 7 to be uncovered, whereby the water will flow from the chamber 1, 80 through the orifice 7 and aperture or apertures 10, to the sponge.

Having thus described my invention, what I claim is—

In a moistener for gummed surfaces, the 85 combination of a water-chamber; a sleeve fitted around one end thereof and having its exterior surface screw-threaded; a cap screw-threaded upon said sleeve to close one end of the water-chamber; a cap on the opposite end 90 of the said chamber provided with a discharge-orifice, and having its exterior surface screw-threaded; a cup-shaped valve screw-threaded upon said cap and having one or more apertures therein; a sponge-receptacle screw-threaded upon said valve; a pin projecting 95 inwardly from the said receptacle to retain the said sponge therein; and a sponge projecting from the said receptacle.

In testimony whereof I affix my signature 100 in the presence of two witnesses.

WILLIAM A. MURRAY.
